Inventor,

Ralph E. Barker,
By *Albert H. Davis*, Atty

UNITED STATES PATENT OFFICE.

RALPH E. BARKER, OF LYNN, MASSACHUSETTS, ASSIGNOR TO GENERAL ELECTRIC COMPANY, A CORPORATION OF NEW YORK.

VARIABLE REACTIVE COIL.

No. 868,752.

Specification of Letters Patent.

Patented Oct. 22, 1907.

Application filed January 23, 1907. Serial No. 353,627.

To all whom it may concern:

Be it known that I, RALPH E. BARKER, a citizen of the United States, residing at Lynn, county of Essex, State of Massachusetts, have invented certain new and useful Improvements in Variable Reactive Coils, of which the following is a specification.

My invention relates to coils of variable reactance for regulating the voltage supply to alternating-current devices, as for instance, to small alternating-current ¹⁰ motors. Such coils have been made heretofore with open-circuited magnetic cores, but such a construction is objectionable, since in operation it is ordinarily noisy, because of the air-gap.

By my invention I obtain with a closed-circuit core, ¹⁵ which is noiseless, the same results that have been obtained heretofore with open-circuit cores. I secure this result by arranging the core with a closed magnetic circuit, but with varying cross-section; a portion of the core being arranged to be highly saturated by normal ²⁰ current-flow through the coil. By shifting the coil from the saturated to an unsaturated portion of the core, the reactance of the coil is made to vary widely.

My invention will best be understood by reference to the accompanying drawings, in which

²⁵ Figure 1 shows a side elevation of a reactive coil arranged in accordance with my invention; Fig. 2 shows a plan view of the same; and Fig. 3 is a diagram of connections.

In the drawings, A represents a suitable base, on ³⁰ which the coil B is firmly mounted.

C represents a laminated circular core, which is inter-linked with the coil, and which has a circular opening eccentric with respect to the periphery of the core, as is clearly shown in Fig. 2. With this arrangement the ³⁵ cross-section of the core varies, and the core proportioned at its point of smallest cross-section to be highly saturated by the current in the coil B. The core C is riveted to a suitable support D carried by the controlling lever E, which is mounted on the pivot e, with its ⁴⁰ axis concentric with the sectional opening in the core. By rotating the lever E on its pivot, the core C is rotated around the side of the coil which it incloses, and the cross-section of the portion of the core inclosed by the coil is varied. A clamping-screw F is provided on ⁴⁵ the lever E, and travels in the semi-circular slot f in the base A. By means of this screw and slot a core may be clamped in any position of the core.

When the core is in the position shown in Figs. 1 and 2, the coil surrounds the portion of the core of smallest cross-section. This part of the core is highly saturated, ⁵⁰ so that the core has little effect on the coil-reactance, but when the core is shifted to bring the section of maximum cross-section within the coil, the reactance of the coil is greatly increased.

In Fig. 3 I have shown the coil connected for controlling the voltage supplied to a small induction motor. In this figure G represents a source of alternating current, H a step-down transformer, I the main winding of the motor, and J a starting winding adapted to be cut out of circuit by the switch K. The motor windings are merely indicated diagrammatically, since the construction and connections of the motor form no part of my invention.

What I claim as new and desire to secure by Letters Patent of the United States, is:

1. A variable reactive coil comprising a core forming a closed magnetic circuit of varying cross-section and a winding on said core, the core and winding being relatively adjustable.

2. A variable reactive coil comprising a laminated circular core with a central opening eccentric with respect to the periphery of the core, and a winding interlinked with said core, the core and winding being relatively ⁷⁰ adjustable.

3. A variable reactive coil comprising a stationary winding and a laminated core interlinked therewith, said core forming a closed magnetic circuit of varying cross-section and being adjustable relatively to said winding.

4. A variable reactive coil comprising a stationary winding and a laminated circular core having a central opening ⁸⁰ surrounding said winding eccentric with respect to the periphery of the core, said core being pivotally mounted on an axis concentric with said central opening.

5. A variable reactive coil comprising a core forming a closed magnetic circuit of varying cross-section and a winding on said core, the core and winding being relatively adjustable, and means for clamping the core and winding in fixed relative positions.

6. A variable reactive coil comprising a stationary winding and a laminated circular core having a central opening ⁹⁰ surrounding said winding eccentric with respect to the periphery of the core, said core being pivotally mounted on an axis concentric with said central opening, and clamping means for said core.

In witness whereof, I have hereunto set my hand this ⁹⁵ twenty-first day of January, 1907.

RALPH E. BARKER.
